UNITED STATES PATENT OFFICE.

HAMILTON D. GUFFEY, OF UNIONVILLE, MISSOURI.

ROAD DRAG AND HARROW.

No. 888,609.

Specification of Letters Patent. Patented May 26, 1908.

Application filed July 18, 1907. Serial No. 384,394.

To all whom it may concern:

Be it known that I, HAMILTON D. GUFFEY, a citizen of the United States, residing at Unionville, in the county of Putnam and State of Missouri, have invented certain new and useful Improvements in a Combination Road Grader, Drag, and Harrow; and I do declare the following to be a full, clear, and exact description of the invention, such as will enable others skilled in the art to which it appertains to make and use the same.

This invention relates to improvements in a combined road grader, drag and harrow.

The object of the invention is to provide a device of this character which may be readily arranged for use as a road grader and drag, or as a harrow, means being provided whereby the parts may be quickly adjusted for light or heavy work.

A further object is to provide a road grader having means whereby the scraping blades may be adjusted to throw the dirt to the right or left, as desired.

With these objects in view, the invention consists of certain novel features of construction, combination and arrangement of parts as will be more fully described and particularly pointed out in the appended claims.

In the accompanying drawings, Figure 1 is a plan view of my road grader, drag and harrow, with the parts arranged for use as a grader; Fig. 2 is an end view of the same; Fig. 3 is a plan view showing the manner in which the device is adjusted to throw the dirt to one side or the other; Fig. 4 is a longitudinal vertical sectional view showing the device arranged as a combined grader and drag, and showing the seat and draft adjusted for light work; and Fig. 5 is a similar view of the device arranged as a harrow.

In the embodiment of my invention, I provide one or more transversely disposed supporting bars 1, which are hingedly connected together at each end, and in the center by longitudinally disposed links, 2. To the forward side of each of the bars 1 is adapted to be attached reversible scraper blades, 3, said blades being detachably secured to the bars by screws, bolts, or other suitable fastening devices. The blades 3 are preferably curved longitudinally, and are so disposed on the forward sides of the bars 2 that the lower edge of the blade will project slightly below the lower edge of the bars, as shown. When one of the edges becomes worn the blades may be taken off and reversed to bring the

opposite edge into an operative position, thus providing for the use of both edges of the blades.

Adapted to be connected with the front or rear pivot bolt of the central link 2, is a seat supporting standard 4, in the upper rearwardly projecting end of which is formed a slot, whereby the seat 5 may be adjustably secured thereto. The lower end of the standard 4 may also be bolted or otherwise secured in a bolt hole formed in the center link, 2, midway between the bars 1. By connecting the lower end of the seat standard 4 to the front or rear end or center of the link 2, the weight of the rider will be shifted, thereby adapting the device for light or heavy work.

To the upper side of the vehicle supporting bar 1, adjacent to its opposite end, are secured upwardly projecting draft lugs 6, in which are formed a series of vertically disposed openings 7, to one or the other of which is adapted to be connected a suitable draft mechanism. By providing the plurality of openings, 7, the draft mechanism may be adjustably connected thereto, thereby changing the position of the blade supporting bars to cause the machine to do heavy or light work, as desired.

The draft device is here shown and preferably comprises a transversely disposed draft bar, 9, which is secured by chains or other flexible connections, 10, to the draft lugs, 6. Adapted to be slidably engaged with the bar 9 is a clevis or attaching clip, 12, between the rear ends of which is mounted a bearing roller, 13, which is adapted to engage the rear side of the bar 9, and to roll from one end to the other thereof, thereby changing the draft from one side to the other of the machine. To the outer end of the clip 12 is connected a whiffletree 14, to the opposite ends of which are connected swingletrees, 15, to which the draft animals are adapted to be hitched.

By providing an adjustable draft device, such as herein shown and described, the machine may be quickly adjusted to throw dirt either to the right or left hand side of the road by simply placing the foot upon one of the rear corners of the device, which will cause the draft roller and clip to travel to the opposite end of the draft bar, 9, in which position the draft will be applied to the supporting bars to maintain the same in an oblique position, while being drawn over the road, thus causing the dirt

to be thrown to one side or the other of the machine. When it is desired to change the position of the supporting bars and scrapers, it is simply necessary to place the foot on and hold down the opposite rear corner of the device, which will cause the same to turn in the opposite direction, thus providing for the throwing or scraping of the dirt toward the opposite side of the road.

10. When the device is intended to be used simply as a drag, the blades are removed from both of the supporting bars and the latter are drawn over the ground to smooth and pulverize the same.

15. When it is desired to use the machine as a combined scraper and drag, the rear scraping blade is removed from its supporting bar and said bar 1 serves as a drag to follow the scraping blade on the forward supporting bar.

20. When it is desired to use the device for very light work, the rear supporting bar and blade are disconnected entirely from the front bar, and the seat supporting standard is connected to the center pivot bolt of the forward bar, thus providing for a single form of the device.

When the device is to be constructed for use as a harrow, the supporting bars 1 and the connecting links 2 are provided with teeth or spikes, 16, which are adapted to project a suitable distance below the same, as shown.

A road grader and drag constructed as herein shown and described, will be simple, strong, durable and inexpensive in construction, and by providing a draft mechanism for the same such as herein shown, the parts may be quickly changed without the use of levers or other operating devices to throw the dirt to one side or the other of the road.

40. Having thus described my invention, what I claim as new and desire to secure by Letters-Patent, is:

1. In a combined road grader, drag and harrow, a draft device and means whereby said device is connected to the grader to automatically shift the direction of the latter, substantially as described.

2. In a combined road grader, drag and harrow, a draft bar loosely connected thereto, and a clevis slidably on said bar to automatically change the direction of the grader, substantially as described.

3. In a combined road grader, drag and harrow, a draft bar, flexible connections at the opposite ends of said bar to attach the same to the grader, means whereby said connections are adjustably secured to the grader, a clevis to engage said bar, and a bearing roller journaled in said clevis to travel on said bar and slidably connect said clevis therewith, substantially as described.

4. In a combined road grader, drag and harrow, a draft bar loosely connected thereto, a clevis slidable on said bar, to automatically change the direction of the grader,

and means to regulate the grader for light or heavy work, substantially as described.

5. In a combined road grader, drag and harrow, a draft bar loosely connected thereto, a clevis slidable on said bar to automatically change the direction of the grader, a seat mounted on said grader, and means whereby said seat is adjusted so that the weight of the driver is employed to regulate the grader for light or heavy work, substantially as described.

6. In a combined road grader, drag and harrow, a draft bar loosely connected thereto, a clevis slidable on said bar to automatically change the direction of the grader, a seat supporting standard having a slotted upper end and adapted to be adjustably connected at its lower end to the grader, and a seat adapted to be adjustably connected to the slotted upper end of the grader, whereby the weight of the driver is employed to regulate the grader for light or heavy work, substantially as described.

7. A device of the character described, comprising transversely disposed supporting bars pivotally connected together to swing laterally, a draft device, and means whereby said draft device is connected to said bars to automatically shift the latter, and thereby change the direction of the same, substantially as described.

8. A device of the character described, comprising transversely disposed supporting bars, longitudinally disposed links to pivotally connect said bars together, a draft bar loosely connected to one of said supporting bars, and a clevis slidably connected with said draft bar, substantially as described.

9. A combined road grader, drag and harrow, comprising transversely disposed supporting bars, links to pivotally connect said bars together, scraping blades detachably secured to said side bars, a draft bar loosely connected to one of said supporting bars, a clevis, and a roller pivotally mounted in said clevis to engage said draft bar whereby said clevis traverses the same, and thereby automatically shifts the direction of said supporting bars, substantially as described.

10. A combined road grader, drag and harrow, comprising transversely disposed supporting bars, links to pivotally connect said bars together, reversible scraping blades arranged on said bars, a transversely disposed draft bar, flexible connections secured to the opposite ends of said bar to attach the same to one of said supporting bars, a clevis, a bearing roller journaled in said clevis to engage and traverse said draft bar, and means to regulate the grader for light or heavy work, substantially as described.

11. A combined road grader, drag and harrow, comprising a plurality of transversely disposed supporting bars, reversible and removable scraper blades secured to said

bars, a series of apertured links adapted to loosely and detachably connect said bars, harrow teeth adapted to be detachably secured in the apertures of said links, a transversely disposed draft bar, adjustable flexible connections at the opposite ends of said bar to attach the same to said supporting bars, a clevis, a bearing roller journaled therein to engage and traverse said draft bar, a seat supporting standard, adapted to be adjustably connected to one of said links,

and a seat adjustably connected to the upper end of said standard, substantially as described.

In testimony whereof I have hereunto set 15 my hand in presence of two subscribing witnesses.

HAMILTON D. GUFFEY.
